UNITED STATES PATENT OFFICE.

SHERMAN S. LAWSON, OF LIMA, OHIO.

FEED-WATER-HEATING SYSTEM.

1,162,937.

Specification of Letters Patent.

Patented Dec. 7, 1915.

Application filed January 6, 1915. Serial No. 724.

To all whom it may concern:

Be it known that I, SHERMAN S. LAWSON, a citizen of the United States, and a resident of Lima, in the county of Allen and State of Ohio, have invented certain new and useful Improvements in Feed-Water-Heating Systems, of which the following is a specification.

My invention relates to feed water heating systems for boilers, particularly to such systems in which water heating pipes are arranged in the path of the products of combustion which go to generate steam in the boiler.

In water heating systems of the class referred to water is forced into the heating pipes by a pump, injector or other device to be heated by the products of combustion before delivery to the boiler. In these prior heating systems the water in the heating pipes, however, becomes stagnant as soon as the pump or injector is stopped, that is, there will be no circulation through the heating pipes, and there will therefore be a sort of geyser action; the steam generated upon intense heating of the stagnant water causing water to be blown out of the heating pipes thus subjecting the pipes to the danger of becoming overheated or burned.

One of the important objects of my invention is therefore to prevent such overheating of the heater pipes preferably by effecting circulation of the water through the heater pipes when the pump or injector is not operated. In other words, the object is to change the water heater system into an efficient steam producing system when the pump or injector is not operated.

Another important object of the invention is to automatically change the condition from water heating to steam generating in order that as soon as the injector stops circulation will automatically start through the heater pipes and these pipes become evaporative area for efficient generation of steam, and when the injector is again started circulation will stop and water will be injected through the heater pipes and into the boiler in the ordinary manner.

Another object is to provide improved simple and efficient means for automatically controlling the change from one operative condition to another and the means is preferably such that the starting and stopping of the injector will automatically put the

heater system in condition for heating and feeding water or for circulation and steam generation.

My invention can of course be applied to different types of boilers and is particularly adaptable in connection with locomotive boilers. In the accompanying drawings, I have therefore shown the invention applied to a locomotive boiler, and in these drawings Figure 1 is a side elevation of a locomotive boiler showing the feed water attachment applied thereto, Fig. 2 is a front view of the boiler, Fig. 3 is an enlarged sectional view of the mechanism for producing circulation and for controlling the change from water heating to circulating and steam generating conditions or vice versa, Fig. 4 is an enlarged view of controlling valve mechanism showing a different position thereof from that shown in Fig. 3, and Fig. 5 is a horizontal sectional view of a boiler showing a modified arrangement of the water heater piping and connections.

The hot water heating system shown is substantially like that disclosed in my co-pending application Serial No. 823,211, filed March 7, 1914. The locomotive boiler shown has the fire box 11 and the smoke box 12 of usual construction, the fire box tube sheet 13 and the smoke box tube sheet 14 being connected by flues 15, the products of combustion passing from the fire box through these flues into the smoke box and out through the stack 16. The water heating mechanism shown is in the nature of an attachment which can be readily applied and associated with flues of the boiler. As shown the smoke box is provided at its opposite sides with openings 17 and 17' through which the two heater sections 18 and 18' are extended. These two sections are exactly similar and each comprises a header 19 extending through the respective opening in the smoke box and from which a pipe loop or loops 20 extends to be associated with the boiler flues. As shown, each header has an inlet passageway 21 and an outlet passageway 22 in whose inner ends 21' and 22' the ends of pipes 23 and 24 extend, these pipes passing through one of the flues 15 of the boiler substantially full length thereof and being connected together at their inner ends by a fitting 25. Water entering inlet passageway 21 of the header will flow through pipes 23 and 24 and back through the header outlet

passageway 22. During such flow of the water it will be heated by the flue 15 and in the smoke box, the heat in the smoke box being thus taken advantage of and its waste 5 through the smoke stack prevented. Each header is detachably secured in the opening in its respective smoke box opening by means of a flange 26 and bolts 27. In the front wall 28 of each header are cleaning 10 openings 29 and 30 in line with the pipes 23 and 24 and detachable plugs 31 and 32 normally close these openings. In the intermediate wall 33 of each header is the opening 34 in line with opening 32 and pipe 15 34 and is normally closed by a plug 35. In the front wall 36 of the smoke box openings 37 and 37' are provided in line with the plugs through which these plugs can be reached and through which suitable cleaning 20 instruments can be inserted into the pipes 23 and 24 when the plugs are removed. The openings are provided with detachable covers 38 and 38'. The heater pipes can therefore be readily cleaned without removal 25 thereof from the boiler. The pipes are preferably provided with couplings 39 and 40 by means of which the pipes and header may be separated to facilitate installation of the heater sections or entire removal thereof 30 from the boiler.

The inlets 21 of the headers are connected by pipes 41 and 41' with the horizontal section of a T-coupling 42 with the lower end of whose vertical section the water supply 35 pipe 43 is connected, this pipe leading from a pump, injector or other water forcing device 44. The outlets 22 of the headers are connected by pipes 45 and 45' with valve fittings 46 and 46' which communicate with 40 the water space of the boiler preferably at the same level as shown in Fig. 2. When the pump or injector 44 is operating water will flow into pipe 43 and the fitting 42 and will then branch through pipes 41 and 41' 45 and through the respective headers and heater pipes to be heated and will then flow to the opposite sides of the boiler through valve fittings 46 and 46'. To prevent back flow when the injector or pump stops a check 50 valve mechanism 47 is provided in the fitting 42 as clearly shown in Fig. 2.

The system thus far described will operate efficiently for heating the feed water of the boiler. However, unless preventive 55 means are applied the water in the heater sections will become stagnant as soon as the pump or injector 44 is stopped and this water would then be subjected to the intense heat in the flues and the smoke box and there 60 would be a sort of geyser effect. The steam generated would blow water out of the heater sections and the pipes would therefore be exposed and would be in danger 65 of being overheated or burned. One of the important objects of my invention is to pre-

vent such stagnation and to cause circulation through the pipes as soon as the pump stops. I therefore introduce circulating mechanism designated as a whole C. This circulating mechanism is applied to one of 70 the heater sections and comprises a frame or fitting 48 shown as interposed in the pipe 45 leading from the header 18 to the boiler. A nozzle 49 extends into the fitting 48 in line with the pipe section 45^a which connects with the valve fitting 46, and the outer end of this nozzle connects with one end of a valve frame 50 whose other end is connected by pipe 51 with the pipe 43 leading from the injector. The valve frame 50 has the inner 75 and outer valve chambers 52 and 53, the latter being of larger diameter. A valve 54 is adapted to reciprocate in these chambers and has the piston sections 54^a and 54^b. The inner end of the valve has the conical head 80 55 for coöperating with the valve seat 56 while the plug 57 in the outer end of the frame 50 forms a seat for the piston end 54^b. Communicating with valve chamber 52 is a pipe 58 which is in communication 85 with the steam supply of the boiler, being preferably connected with the boiler turret. When the valve is in the outer position shown in Fig. 3 its head 55 is away from seat 56 and valve chamber 52 and the nozzle 90 49 are open to steam flow from pipe 58. When the valve is in its inner position shown in Fig. 4 the valve head 55 seats on seat 56 and closes communication between chamber 52 and the nozzle and disconnects the nozzle 95 from the steam supply.

The operation can now be readily understood. The valves 46 and 46' being always open, the entire heater system is under boiler pressure and this pressure exerted against 105 the valve 54 at piston section 54^a tends to shift this valve to its outer position shown in Fig. 3. The injector 44 operates, however, at a pressure in excess of the boiler pressure and when it is started the pressure of the 110 water through tap 51 and against the larger diameter piston 54^b of the valve will positively and effectively shift this valve inwardly to disconnect the nozzle 49 from the steam supply pipe 58. Water is then charged past the 115 check valve mechanism 47 through the two heater sections and into the boiler, it being heated on its passage through the headers and tubes. So soon, however, as the injector stops the pressure in pipe 43 drops and 120 check valve 47 closes and the pressure in the heater sections and in valve chamber 52 will prevail and the valve 54 will be shifted to its outer position (Fig. 3) and pipe 58 will be connected with the nozzle through which 125 the steam will flow. The steam will pass out of the nozzle at high velocity and will force the water directly in front of it through the pipe section 45^a and valve 46 into the boiler thus reducing the level at 130

that part of the water heating system. The pressure at valve 46' will then force water into the heater system to replace the water forced into the boiler by the steam jet, thus creating a circulation. The steam jet does not have to suck the water around through the heater system but all that it does is to force a little water away from the nozzle to create unequal pressure at that end of the heating system and the boiler pressure at the other end of the system will then force the circulation. Thus when the injector stops, circulation is immediately automatically forced through the headers and flue pipes and connections of the heating system, the system being changed automatically from a feed water heating system to a steam producing system, the water circulating from one side of the boiler through the system to the other side to be converted into steam. There is then no danger of overheating or burning of the heater pipes and the steam producing efficiency of the boiler as a whole is increased. When the injector is started the conditions are automatically changed and water is injected into the system to be heated on its passage through the headers and flue pipes before delivery to the boiler. The mechanism for changing from one condition to another upon stopping or starting of the injector is very simple and reliable and is entirely automatic in its operation.

I do not of course desire to be limited to the precise construction, arrangement or operation shown and described as changes and modifications are no doubt possible which would still come within the scope of the invention.

40 I claim as follows:

1. The combination of a steam boiler, of a water loop connected at its ends with the water space of the boiler and having an intermediate section arranged in the path of the products of combustion which go to generate steam in the boiler, an injector connected with said loop for forcing boiler feed water therethrough into the boiler, and means automatically controlled upon stopping of said injector for positively forcing circulation of the boiler water through said loop, said means effecting circulation through said loop independently of the normal restricted circulation which might be produced by differences in temperature in the loop.

2. The combination with a steam boiler, of a water loop connected at its ends with the water space of the boiler and having an intermediate section arranged in the path of the products of combustion which go to generate steam in the boiler, a water supply conductor connected with said loop and a check valve controlling said connection to admit flow of water into the loop but to pre-

vent flow therefrom, an injector connected with said water conductor for forcing water through the loop into the boiler, and means automatically controlled upon stopping of said injector for positively forcing unequal pressure in the loop and thereby pronounced and continuous circulation of boiler water through said loop. 70

3. The combination with a steam boiler, of a water loop connected at its ends with the water space of the boiler and having an intermediate section arranged in the path of the products of combustion which go to generate steam in the boiler, a water supply conductor connected with said loop and a check valve controlling said connection to admit flow of water into the loop but to prevent flow therefrom, an injector connected with said water conductor for forcing water through the loop into the boiler, and means automatically controlled upon stopping of the injector for positively reducing the level of the water at one end of the loop to thereby cause continuous circulation of boiler water through said loop. 75 80 85

4. The combination with a steam boiler, of a water loop connected at its ends with the water space of the boiler and having an intermediate section arranged in the path of products of combustion which go to generate steam in the boiler, an injector connected with said loop for causing parallel flow of water through the ends thereof into the boiler, and means for forcing pronounced and continuous serial circulation of boiler water through said loop when said injector ceases to operate. 90 95 100

5. The combination with a steam boiler, of a water loop having its ends connected with the water space of the boiler and having an intermediate section arranged in the path of the products of combustion which go to generate steam in the boiler, an injector for injecting water through said loop into the boiler, and means automatically controlled upon stopping of the injector for positively forcing unbalance of pressure in the loop to cause pronounced circulation of boiler water therethrough. 105 110

6. The combination with a steam boiler, of a water loop connected at its ends with the water space of the boiler, and having an intermediate section arranged in the path of the products of combustion which go to generate steam in the boiler, a water supply conductor and a check valve controlling its connection with said loop, an injector connected with said water supply conductor for forcing water therethrough into the loop and into the boiler, a water circulation forcing device interposed in said loop and controlled conjointly by the boiler steam pressure and injector pressure to force the circulation of boiler water through said loop when the injector is not operating. 115 120 125 130 135

7. The combination with a steam boiler, of a water loop connected at its ends with the water space of the boiler and having an intermediate section arranged in the path 5 of the products of combustion which go to generate steam in the boiler, an injector connected with said loop for forcing water therethrough into the boiler, a circulating device connected with said loop for forcing 10 circulation of boiler water therethrough, means controlled by the feed water pressure for rendering said circulating device inoperative when the injector is operating, and means controlled by the boiler steam pressure 15 for rendering said circulating device operative when the injector is not operating.
8. The combination with a steam boiler, of a water loop having its ends connected with the water space of the boiler and having an intermediate section arranged in the path 20 of the products of combustion which go to generate steam in the boiler, an injector connected with said loop and with a source of water, a circulation forcing device 25 connected with said loop, and valve mechanism controlled conjointly by the injector pressure and the boiler steam pressure to cause said device to become inoperative when the injector is operating and to cause 30 said device to become operative as soon as the injector stops.
9. The combination with a steam boiler, of a water heating system comprising water conductors arranged in the path of the products 35 of combustion which go to generate steam in the boiler, a water forcing device for forcing feed water through said conductors to be heated therein before delivery to the boiler, and mechanism for forcing 40 pronounced circulation of boiler water through said heating system when said water forcing device ceases to operate whereby to convert said heating system into an efficient steam generating system.
10. The combination with a steam boiler, of a water loop having its ends connected with the water space of the boiler and having an intermediate section arranged in the path 45 of the products of combustion which go to generate steam in the boiler, an injector for injecting feed water through said loop into the boiler, and means automatically controlled upon stopping of the injector for injecting steam into said loop to 50 thereby effect unbalance of pressure therein and forced circulation therethrough of the boiler water.

11. The combination with a steam boiler, of a water loop having its ends connected 55 with the water space of the boiler and having an intermediate section arranged in the path of the products of combustion which go to generate steam in the boiler, an injector for injecting feed water through said loop into the boiler, a water circulating de-

vice interposed in said loop near one of its connections with the boiler, and means whereby said circulating device is controlled when the injector stops to continuously displace the water in said loop to cause pressure unbalance and circulation of water through the loop and the efficient generation of steam therein. 70

12. The combination with a steam boiler, of a loop connecting at its ends with the 75 boiler below the water level therein and subjected at an intermediate section to the products of combustion which go to generate steam in the boiler, an injector for forcing water through said loop into the boiler, a circulating device connected with the loop at one end thereof, and means automatically controlled upon stopping of the injector for causing said circulating device to force water from the corresponding loop end into 80 the boiler whereby to effect difference in pressure at the loop ends resulting in circulation of boiler water through the loop.

13. The combination with a steam boiler, of a loop connecting at its ends with the 85 boiler below the water level therein and subjected at an intermediate section to the products of combustion which go to generate steam in the boiler, an injector for forcing water through said loop into the boiler, a 90 circulating device connected with one end of the loop, and means conjointly controlled by the steam pressure of the boiler and the water pressure from the injector for disconnecting said circulating device from service 95 when said injector is operating and for automatically connecting the circulating device for service when the injector stops and for then causing continued forcing of water into the boiler from the corresponding end 100 of the loop to thereby effect difference in pressure at the loop ends resulting in continued circulation of boiler water through 105 the loop.

14. The combination with a steam boiler, 110 of a loop connecting at its ends with the boiler below the water level therein and subjected at an intermediate section to the products of combustion which go to generate steam in the boiler, an injector for forcing 115 water through said loop into the boiler, a frame interposed in one end of the loop and forming a chamber, a nozzle projecting into said chamber, a valve housing connected with said frame and a valve therein, said 120 valve housing connected at one end to be subjected to the water pressure caused by the injector in operating and the other end of the housing being connected to be subjected to steam pressure from the boiler, the 125 arrangement being such that the water pressure will shift the valve to disconnect the steam supply from the housing when the injector is working to thereby render the nozzle ineffective and the steam pressure 130

will shift the valve to connect the nozzle with the steam connection when the injector stops whereby steam will then be projected into the corresponding loop end in the direction of its connection with the boiler to continuously force water through the loop end into the boiler to thereby cause difference in pressure at the loop ends resulting

in circulation of boiler water through the loop.

In witness whereof I have hereunto set my hand this 2nd day of January, 1915.
